UNITED STATES PATENT OFFICE.

HUGO LOEWENBACH, OF MILWAUKEE, WISCONSIN.

TABLET AND FILE HOLDER.

SPECIFICATION forming part of Letters Patent No. 653,683, dated July 17, 1900.

Application filed December 27, 1898. Serial No. 700,369. (No model.)

To all whom it may concern:

Be it known that I, HUGO LOEWENBACH, a citizen of the United States, residing at Milwaukee, in the county of Milwaukee and State 5 of Wisconsin, have invented new and useful Improvements in Tablet and File Holders, of which the following is a specification.

My invention relates to improvements in tablet and file holders.

10 The object of my invention is to provide a convenient means for engaging, holding, and disengaging tablets, files, music-sheets, and other similar articles for which a temporary binder or holder is desired.

15 In the following description reference is had to the accompanying drawings, in which—

Figure 1 is a plan view of my invention in its open position and showing the same in use for holding carbon copying-tablets. Fig. 2 is 20 a sectional view drawn on line $x-x$ of Fig. 1. Fig. 3 is a similar view with the paper-holding catches in their raised position.

Like parts are identified by the same reference-letters throughout the several views.

25 A and B are the covers of my improved holder, secured together by a flexible binding C. The cover A is preferably provided with the aperture or cut-away portion D, over which, on the inner face of the cover, I have 30 secured a plate E, which is constructed to yield elastically when force is applied thereto through the aperture or in any other manner, so that the plate and cover become separated, except at the securing-points. Looped

35 catches F are rigidly secured to the plate near the edge thereof opposite the fastening-points and with their free ends projecting over the edge and adapted to engage in perforations or recesses G in the cover, as best

40 shown in Figs. 2 and 3. It is obvious that by applying pressure to the plate E through the aperture D that end of the plate which is provided with the catches will be lifted or separated from the cover to withdraw the free 45 ends of the catches F, from the recesses G, whereupon the tablets, music-sheets, or other articles to be held may be inserted under the ends of the catches and engaged thereby.

The articles to be held are preferably per- 50 forated preparatory to their insertion in the holder, the perforations being so located that

the catches will register therewith. How- 55 ever, the ends of the catches may obviously be pointed, so as to perforate the sheets in case the latter are previously unperforated.

It will be observed that the plates E are se- 60 cured to the face of the cover A and project from the securing-points toward the inner end of the cover—*i. e.*, that end which is con- 65 nected to the cover B by the binding C—and the catches are therefore located in an ap- 70 propriate position to serve as a binder for the articles inserted in the holder. It will also be observed that the catches are constructed in the form of a loop or inverted U, this con- 75 struction being important in that the respec- tive sheets of the tablet or other articles in- 80 serted in the holder are permitted to remain flat upon the respective covers by reason of the fact that they are independently held in place by the opposing sides of the loops which form the catches.

Having thus described my invention, what I claim as new, and desire to secure by Letters Patent, is—

1. A tablet and file holder, comprising a 75 cover provided with an aperture or opening therein; a plate secured to the inner face of said cover and projecting over said opening, and adapted to yield elastically under pres- 80 sure applied through the opening; and catches secured to said plate, adapted to engage, and serve as a binder for, the contents of the holder.

2. A tablet and file holder, comprising a 85 cover provided with an aperture or opening therein; and catches elastically secured to the inner face of said cover, adapted to be actuated by pressure applied through said opening in the cover, said catches being 90 adapted to engage, and serve as a binder for, the contents of the holder.

3. A tablet and file holder comprising a 95 cover; a plate yieldingly secured to one of the faces thereof, and looped catches rigidly secured to said plate, with their free ends pro- jecting over the edge.

4. A tablet and file holder, comprising a 100 pair of covers secured together by a flexible binding or back; a flat plate normally par- allel with, and yieldingly secured to, one of the covers; looped catches rigidly secured to

said plate, with their free ends projecting over the edge. | the edge and adapted to register with perforations or recesses in the cover. 10

5. A tablet and file holder, comprising a pair of covers secured together by a flexible binding or back; a flat plate normally parallel with, and yieldingly secured to, one of the covers; looped catches rigidly secured to said plate with their free ends projecting over

In witness whereof I have hereunto set my hand this 24th day of December, 1898.

HUGO LOEWENBACH.
